UNITED STATES PATENT OFFICE.

WILLIAM P. DILTS, OF BROOKLYN, NEW YORK, ASSIGNOR, BY MESNE ASSIGNMENTS, TO DANE MANUFACTURING COMPANY, OF NEWARK, NEW JERSEY, A CORPORATION OF NEW JERSEY.

SIPHON-HEAD.

1,184,633.

Specification of Letters Patent.

Patented May 23, 1916.

Application filed March 26, 1914. Serial No. 827,389.

To all whom it may concern:

Be it known that I, WILLIAM P. DILTS, a citizen of the United States, residing at Brooklyn, in the county of Kings and State 5 of New York, have invented new and useful Improvements in Siphon-Heads, of which the following is a specification.

This invention relates to improvements in siphon heads and its object is to simplify the 10 construction, reduce the cost and to promote the efficiency of these devices, to provide a siphon head which shall be more sanitary than any construction now used or known, and which shall be incapable of breakage 15 or destruction; and finally, to provide a siphon head having a connection of the most efficient character with the bottle with which it is combined and with the siphon tube which projects into said bottle.

20 The above objects are attained by a construction wherein the siphon head is composed of compressed non-corrosive material, such, for example, as is used for electrical insulation and is well known under the trade 25 names of "bakelite" or "condensite" or "hi-heet," the said head being pressed into the shape determined upon and the dies used in this operation forming the interval chamber and liquid ducts.

30 The invention also involves a novel relation between the siphon head and the bottle, between the siphon head and the siphon tube which projects into the bottle, and between the siphon head and the valve; and finally, 35 a novel construction of valve.

An embodiment of the invention is illustrated in the accompanying drawings, wherein:

Figure 1 is a vertical, longitudinal section 40 view of a siphon head in which the features of the invention are incorporated, the valve being shown in closed relation; Fig. 2 is a fragmentary view similar to Fig. 1, the valve, however, being shown in open 45 relation; Fig. 3 is a detail sectional view of certain features of the valve; Fig. 4 illustrates in elevation, top and bottom plan, a core which enters into the construction of the valve; Fig. 5 is a detail elevation, partly 50 in section, of the valve; Fig. 6 is a detail sectional view showing the relation between

the valve and its operating button or plunger; Fig. 7 is a detail sectional view showing the relation between the siphon tube and the sleeve which connects said tube and the 55 siphon head; Fig. 8 is a bottom plan view thereof.

Similar characters of reference designate corresponding parts throughout the several views.

60 The siphon head, designated generally as 1, is composed wholly of a material which is exceedingly tenacious, substantially non-breakable, non-corrosive, impervious to moisture or gas, and capable of being 65 pressed or molded into the shape desired and of permanently retaining said shape without further treatment. Material of the same character is used in the make-up of various parts of the construction which will 70 be specifically pointed out as the description proceeds. A material which satisfies the requirements stated and which, so far as I am now aware, is the most suitable for the 75 purposes in view, is the compressed non-corrosive material which is in common use at the present time as an electrical insulation and is well known under the trade names of "bakelite," "condensite" or "hi-heet," this material being a molding mix- 80 ture composed of a condensation product of phenol and formaldehyde or its equivalents and a suitable filling, such as asbestos or vegetable fiber.

85 The siphon head disclosed relates broadly to the type of construction shown, for example, in the Lukacsevics Patents No. 1,040,926, granted October 1, 1912, and No. 1,061,857, granted May 13, 1913, which type 90 of construction embodies the siphon head proper 1 having the liquid discharge duct 2 and an axial bore communicating with said duct the said bore having at its lower end a relatively large valve chamber 3 and inwardly of said valve chamber a liquid passage 4; a valve designated generally as 5 and co-acting with a seat 6 intervening between the chamber 3 and the passage 4; a valve-operating button 7 arranged in an axial recess 8 at the upper end of the siphon 95 head, a spring 9 acting on the button and tending to hold the valve normally closed; 100

and a neck ring 10 which surrounds the neck of the bottle and secures the siphon head in position. The siphon head is of course employed in connection with the usual siphon tube 11 which projects into the bottle.

The combination of elements above specified is common to the type of construction disclosed in the said Lukacsevics patents, but the present invention involves substantial differences in the construction of certain specified elements of said combination, and certain differences in the relation of particular elements of the combination.

The siphon head proper 1 is composed of compressed non-corrosive material, as above explained, and this same material is used in the production of the neck ring 10; of the sleeve 12 which holds the siphon tube 11 in position; of the valve and its appurtenances, and preferably of the button 7.

The neck ring co-acts with a depending internally-threaded flange 13 integral with the head 1 and concentric to the bore of said head. The head 1 is formed in its under-face with an annular recess 14 which intervenes between the flange 13 and between an inner annular flange 15, the recess 14 enclosing a sealing gasket 16 of the usual material, and construction.

The valve chamber 3 is internally threaded as at 17 and the sleeve 12 is externally threaded, its threads matching with the threads 17. The said sleeve is fitted in the lower portion of the valve chamber and is thus joined directly to the siphon head. The upper end of the tube 5 fits snugly within the sleeve and said tube is preferably positively held against movement relative to said sleeve by the agency of cement 18 arranged adjacent the upper and lower ends of the sleeve. The sleeve 12 thus provides a rigid connection between the siphon tube 11 and the siphon head. Liability of breakage of the bottle by reason of a sudden jar imparted to the siphon head is prevented by reason of the fact that the gasket 16, apart from its sealing function, provides a cushion which takes up jars. To provide for its convenient application to and removal from the siphon head, the sleeve 12 is made of a square cross section as shown in Fig. 8.

The valve 5 includes a core 19 in the form of a corrugated metal bar of square cross section, said core having a bifurcated lower end 19^a of inverted V-shape. The valve also includes a sleeve 20 which surrounds the core 19 and is composed of the same material as the head 1, e. g., compressed non-corrosive material, as above described, the said sleeve being compressed or molded about the said core. The sleeve 20 at its lower end is formed with a double coniform head 21 which is compressed or molded upon the bifurcated end 19^a of the core. The head 21 constitutes the body of

the valve proper and is complemented by a relatively soft rubber facing 22 which is vulcanized upon said head, the material of which said head is composed, e. g., compressed non-corrosive material, being capable of withstanding vulcanizing heat. The marginal portions of the rubber facing 22 bear against shoulders 23 and 24, the shoulder 23 surrounding the head 21 and the shoulder 24 occurring at the junction of said head and the sleeve 20 and overhanging the head.

A portion of the core 19 at the upper end thereof is left exposed, i. e., is not surrounded by the sleeve 20, and this exposed portion of the core is utilized to connect the valve 5 and the button 7 and projects into a central opening in the top of said button, which opening preferably has an hour-glass shape from end to end, as shown. The union of the valve and the button is completed by a filler of soft metal 25 which is poured in said opening in the top of the button, completely filling the same and of course taking a grip upon the corrugations of the bar 19. The opening in which the filling 25 is poured is closed at its lower end by a washer 26 which takes the thrust of the upper end of the spring 9 by which the valve 5 is held normally closed, the said spring being arranged in a recess 27 internal to the button 7 and at its lower end bearing against a washer or wear-piece 28 which is imposed upon the web 29 which intervenes between the recess 8 in which the button 7 works and the liquid passage 4 and snugly surrounds the sleeve 20. The wear-piece 28 preferably rests upon a packing ring 30, the office of which is to prevent any escape of gas from the passage 4 through the web 29.

As previously stated, the siphon head proper is formed by compressing the material of which said head is composed in a suitable mold embodying properly shaped dies, and the said head requires no baking or other extraneous steps for its production, the use of a high pressure in the molding operation being all that is required. It is necessary, however, that the axial bore of the head which comprises the chamber 3 and the passage 4 should be of no greater diameter at its inner end than at its outer end, since it would be impractical to produce the head in the manner described were the bore of the head of greater diameter at its inner end than at its outer end.

The material of which the head is composed is thoroughly hygienic and sanitary, it is impervious to moisture and gases; it is capable itself of furnishing the required sealing surfaces by which the escape of gas at the various joints of the head and bottle neck and crevices or interstices is efficiently prevented; it is exceedingly tenacious, possessing great tensile strength and having no

brittleness; it lends itself to desired ornamental configurations; it is relatively light in weight and of smooth texture; and may be quickly and inexpensively molded into the shape desired. Since the said material requires no baking to set it in its ultimate form, and is impervious to moisture and gas, the joint between the neck ring and the lower portion of the siphon head proper is greatly superior to the ordinary joint involving a soft metal neck ring.

Having fully described my invention, I claim:

1. In combination, a siphon head body composed wholly of "bakelite" and having an internal bore providing a valve chamber, a liquid passage inwardly of the valve chamber and a valve seat between said chamber and passage and having a liquid discharge duct leading from said passage, a valve coöperating with said seat and having its body and stem integrally formed of material the same as that of said body, a button for operating the valve, the valve chamber being internally threaded, a siphon tube, and a sleeve composed of material the same as that of said body fitted upon the upper end of the siphon tube and having threads to match with the threads of the valve chamber.

2. In combination, a siphon head body composed wholly of "bakelite" and having an internal bore providing a valve chamber, a liquid passage inwardly of the valve chamber and a valve seat between said chamber and passage and having a liquid discharge duct leading from said passage, a valve coöperating with said seat and having its body and stem integrally formed of material the same as that of said body, a button for operating the valve, the valve chamber being internally threaded, a siphon tube and a sleeve of hard, non-corrosive material fitted upon the upper end of the siphon tube and having threads to match with the threads of the valve chamber.

3. In combination, a siphon head body composed wholly of "bakelite" and having an internal bore providing a valve chamber, a liquid passage inwardly of the valve chamber and a valve seat between said chamber and passage and having a liquid discharge duct leading from said passage, the body also having a depending, annular flange, a neck ring co-acting with said flange to secure the body upon a bottle, a siphon tube, a sleeve of hard non-corrosive material carrying the siphon tube and fitted within the valve chamber, being thereby directly attached to said body, a sealing gasket adjacent the base of said flange and concentric to said sleeve, a valve coöperating with said seat and having its body and stem of non-corrosive material and a button for operating the valve.

4. In combination, a siphon head body composed wholly of "bakelite" and having an internal bore providing a valve chamber, a liquid passage inwardly of the valve chamber and a valve seat between said chamber and passage and having a liquid discharge duct leading from said passage, the body also having a depending, annular flange, a neck ring co-acting with said flange to secure the body upon a bottle, a siphon tube, a sleeve composed of material the same as that of said body carrying the siphon tube and fitted within the valve chamber, being thereby directly attached to said body, a sealing gasket adjacent the base of said flange and concentric to said sleeve, a valve coöperating with said seat and having its body and stem composed of material the same as that of said body and a button for operating the valve.

5. In combination, a siphon head body composed wholly of "bakelite" and having an internal bore providing a valve chamber, a liquid passage inwardly of the valve chamber and a valve seat between said chamber and passage and having a depending annular flange, a neck ring composed of material the same as that of said body and having threaded engagement with the flange to secure the body upon a bottle, a siphon tube, a sleeve composed of material the same as that of said body, carrying the siphon tube, and threaded directly to the wall of the valve chamber, a sealing gasket adjacent the base of said flange and concentric to said sleeve, a valve coöperating with said seat and having its body and its stem of non-corrosive material and a button for operating the valve.

6. In combination, a siphon head body having a liquid passage provided with a valve seat and a valve coöperating with said seat and comprising a corrugated metal bar having a square cross-section and forming a core, and a sleeve of "bakelite", molded upon said bar and having its lower end formed to provide a valve body for coöperation with said seat.

7. In combination, a siphon head body composed wholly of "bakelite", and having an integral, depending, annular flange and an internally threaded bore, a neck ring composed of material the same as that of said body and having threaded engagement with the flange to secure the body upon a bottle, a siphon tube, and a sleeve carrying the siphon tube and composed of material the same as that of said body, said sleeve being engaged with the threads of said bore and said body having its under surface provided with an annular gasket-receiving recess.

8. In combination, a siphon head body composed wholly of "bakelite", and provided with a depending, annular, integral

flange to fit over the bottle neck, with an internally threaded bore, and with an internally threaded, integral flange concentric to said first-named flange and forming a downward continuation of said bore, said body having an annular gasket-receiving recess between said flanges, a siphon tube, and a sleeve carrying said siphon tube and composed of material the same as that

of said body, said sleeve engaging the 10 threads of said bore.

In testimony whereof I have hereunto set my hand in presence of two subscribing witnesses.

WILLIAM P. DILTS.
